UNITED STATES PATENT OFFICE.

JOHN J. McINTYRE, OF HARTFORD, CONNECTICUT.

INTERNAL-COMBUSTION ENGINE.

1,022,492.

Specification of Letters Patent.

Patented Apr. 9, 1912.

Application filed April 12, 1910. Serial No. 555,046.

To all whom it may concern:

Be it known that I, JOHN J. McINTYRE, a citizen of the United States, residing at Hartford, in the county of Hartford and State of Connecticut, have invented a new and useful Improvement in Internal-Combustion Engines, of which the following is a specification.

This invention relates to internal combustion engines of the two-cycle type, having an auxiliary piston arranged to cause the spent gases to be forced from the working cylinder, and to pump live explosive mixture into the working cylinder after it has been scavenged.

The object of the invention is to provide a very simple construction with the ports and the pump piston so arranged with relation to the working piston, that the pump piston acts with the working piston to compress air in the crank case, and after the air is under sufficient pressure, allow that air to flow into the working cylinder as the working piston reaches the lower end of its stroke and the exhaust port is opened, thereby scavenging the working cylinder with compressed fresh air. The pump piston which acts as a valve to admit and cut off the supply of scavenging air, and also to admit and cut off the supply of explosive mixture, then forces the charge of explosive mixture into the working cylinder which has been cleared. Separate ports are provided for the admission to the pump cylinder of explosive mixture and scavenging air, and there are separate passages from the pump cylinder, on opposite sides of the pump piston, to the working cylinder. As a result of this arrangement, all spent gases are driven by fresh air from the working cylinder and the cylinder cooled and cleaned of any incandescent carbon which might remain therein and cause premature explosion, before a charge of fresh mixture is forced therein, which charge will always be the same and of maximum quantity. Furthermore, as the pump piston does not force fresh mixture into the working cylinder until after that cylinder has been scavenged, and the working piston started on its upward movement, none of the fresh charge is lost through the exhaust, and the engine cannot accidentally kick back and reverse.

Figure 1 of the accompanying drawings shows a sectional elevation of a two-cycle internal combustion engine which embodies

the invention, with the working piston in its lowest position and just ready to rise, and the pump piston started to rise. When the pistons are in these positions, the exhaust port is fully open, and the air passage from the pump cylinder is opened so as to permit air which has been compressed in the crank case by the downward movements of the two pistons, to flow into the working cylinder and drive out the spent gases. Fig. 2 is a similar view with the pump piston at the upper limit of its movement, and the working piston moving upwardly and compressing a fresh charge of explosive mixture which has been forced above it by the upward movement of the pump piston. When the pump piston is in this position, the port for the entrance of the scavenging air into the crank case is open. Fig. 3 is a like view with the working piston partly down and just before the exhaust port and the scavenging air passage are opened. In this view the pump piston is shown at the lower limit of its movement, in which position the mixture port is opened for the inflow of a fresh charge to the top of the pump cylinder, and the scavenging air passage is also opened so that after some further downward movement of the working piston air, which is already under some compression, will be driven from the crank case into the working cylinder above the piston.

The working cylinder, 1, is made of the usual material and of the desired dimensions. The cylinder shown is provided with an ordinary water jacket 2 and a spark plug 3 is placed in an opening at the top. On one side of the working cylinder is the pump cylinder 4. This cylinder is shown as considerably smaller than the working cylinder, but it may have any desired dimensions. Secured to the bottom so as to tightly inclose the lower ends of the working and pump cylinders, is the crank case 5. The exhaust port 6 opens from one side of the working cylinder approximately at about the middle of its length. In the side of the pump cylinder is a gas port 7 which is designed to be connected with the carbureter or vaporizer which supplies the live explosive mixture of gas and air. Below the gas port is an air port 8 for the admission of the scavenging air. Leading from the top of the pump cylinder to the working cylinder is a passage 9. In this passage is a spring closed check valve 10. Leading from

the pump cylinder to the working cylinder is a passage 11.

The main shaft 12 in the crank case has the usual crank 13. The crank is connected

5 by the rod 14 with the working piston 15.

The pump shaft 16 has a crank 17 in the crank case. This crank is connected by the rod 18 with the pump piston 19 which has an opening 20 through one side near its 10 head. A gear 21 keyed to the main shaft meshes with a gear 22 keyed to the pump shaft. These parts are desirably so timed that the pump piston crank is a few degrees in advance of the working piston crank.

15 The main crank gives the working piston such a stroke, and that piston is of such length, that when the piston is way down, the exhaust port and the scavenging air passage from the pump cylinder are fully open, 20 and when this piston is way up, the exhaust port and this air passage are closed. The pump piston is of such length and has such a stroke that when it is way down, the gas port is open, and the air passage from the 25 pump cylinder is open through the hole in the side of the pump piston, and when the pump piston is way up, this air passage is closed and the scavenging air port is open.

When a charge is exploded the working 30 piston is near the top of its cylinder, and the gas inlet passage, the air inlet passage, and the exhaust port are shut off. At this time, the pump piston is up but is on its way down with the scavenging air port open. As the working piston is driven 35 down, and the pump piston moves down in advance of it, the scavenging air port is closed and then all of the air below the pistons and in the crank case is subjected to 40 more or less compression until the working piston uncovers the exhaust port and the scavenging air passage, allowing the compressed scavenging air in the crank case to flow into the working cylinder and drive the 45 spent gases out through the exhaust port. When the pump piston is way down, the gas port is uncovered, allowing mixture to 50 flow into the partially exhausted pump cylinder above the piston. As the pump piston moves upwardly, it cuts off the gas port, and after the working cylinder has been 55 scavenged, forces the charge past the check valve and into the working cylinder. During this time of course the working piston is coming up and compressing the charge which is thus forced in by the pump piston.

In this engine the pump piston acts to 60 cause compression of fresh air in the crank case and then allows that air to flow into the working cylinder for the purpose of driving out the spent gases. The pump piston also draws in fresh mixture and forces that gas into the working cylinder, thereby always injecting the same full charge, none 65 of which escapes through the exhaust, and

which is not weakened by spent gases, nor is liable to be exploded prematurely by incandescent carbon in the cylinder.

The invention claimed is:

1. An internal combustion engine having 70 a cylinder with a working piston, a crank shaft and crank connected with said working piston, a cylinder with a pump piston, a crank shaft and crank connected with said pump piston, a crank case containing the 75 cranks, gearing connecting said crank shafts, a gas port to the upper end of the pump cylinder, a gas passage from the upper end of the pump cylinder to the working cylinder, a valve controlling said passage, an air port to the lower end of the pump cylinder, and an air passage from the lower end of the pump cylinder to the working cylinder, said ports being so located that the pump piston acts as a valve for controlling the inflow of gas and air through said ports, said pump piston having an opening in one side and being of such length and so coacting with said ports and passages that during its upward movement it forces gas 90 through the gas passage into the working cylinder, and during its downward movement it compresses air in the crank case and then permits said compressed air to flow through its opening to the air passage into 95 the working cylinder.

2. An internal combustion engine having a working cylinder, a working piston movable in the working cylinder, a crank and crank shaft connected with the working piston, a pump cylinder, a piston movable in the pump cylinder, a crank and crank shaft for reciprocating the pump piston, a crank case containing the cranks, gearing connecting the crank shafts, with a gas port and an 100 air port opening through one side of the pump cylinder to opposite sides of the pump piston, and a gas passage and an air passage leading from the pump cylinder on opposite sides of the pump piston to the 110 working cylinder, said gas port and air port being so located with relation to each other, and said pump piston being of such length and having such movement that the pump piston acts as a valve for said ports, opening said gas port and closing said air port on its downward movement, and opening said air port and closing said gas port on its upward movement.

3. An internal combustion engine having 120 a working cylinder, a piston movable therein, a crank and crank shaft connected with the working piston, a pump cylinder and a pump piston movable in the pump cylinder, a crank and crank shaft for reciprocating the pump piston, a crank case containing the cranks, and gearing connecting the shafts, said pump cylinder having a gas intake port and an air intake port through 125 one side to opposite sides of the pump pi- 130

- ton, and being connected with the working cylinder by two passages which lead from opposite sides of the pump piston to the explosion side of the working piston, said pump piston moving across and opening and closing said ports and one of said passages during its reciprocation so as to admit gas above and compress air below during its downward movement, and admit the compressed air to and force gas into the working cylinder during its upward movement. 4. An internal combustion engine having a working cylinder, a piston movable therein, a crank and crank shaft connected with the working piston, a pump cylinder, a pump piston movable in the pump cylinder, a crank and crank shaft for reciprocating the pump piston, a crank case containing the cranks, a gear on the working piston crank shaft, an intermeshing gear on the pump piston crank shaft, said gears so engaging that the pump crank moves a few degrees in advance of the working crank, said pump cylinder having a gas intake port and an air intake port through one side to opposite sides of the pump piston, and being connected with the working cylinder by two passages which lead from opposite sides of the pump piston to the explosion side of the working piston, and said pump piston being arranged to move across and to open and close said gas and air intake ports during its reciprocation. 5. An internal combustion engine having a working cylinder and a piston therein, a pump cylinder parallel therewith and containing a piston, connecting means whereby the pistons reciprocate synchronously, said cylinders being connected by two passages that communicate with the pump cylinder respectively on opposite sides of the piston therein, said pump cylinder having a gas port and an air port which are opened and closed by the movements of the pump piston, said ports to the pump cylinder and passages from the pump cylinder to the working cylinder being so located with relation to each other and to the movements of the pump piston that gas is drawn into the pump cylinder through the gas port as a result of the downward movement, and is forced from the pump cylinder through one of said passages into the working cylinder as a result of the upward movement of the pump piston, and air is drawn into the pump cylinder through the air port as a result of the upward movement, and is compressed as a result of the downward movement of the pump piston and then permitted to pass through the other of said passages into the working cylinder. 6. An internal combustion engine having a working cylinder, a piston movable therein, a pump cylinder and a hollow piston movable in the pump cylinder for compressing air during its downward movement and pumping gas to the working cylinder during its upward movement, said pump cylinder having a gas intake port and an air intake port on respectively opposite sides of the pump piston, and being connected with the working cylinder by an air passage and a gas passage which lead from opposite sides of the pump piston to the explosion side of the working piston, said pump piston opening and closing said ports during its movements, and having a port through one side near its head, which port when the piston is in its lowest position communicates with the air passage between the pump cylinder and the working cylinder. 7. An internal combustion engine having a working cylinder, a piston movable therein, a piston rod and crank connected with the working piston, a pump cylinder and a pump piston movable in the pump cylinder, a piston rod and crank connected with the pump piston, gearing connecting said cranks, said cylinders being arranged parallel side by side and connected by two passages that lead from the pump cylinder respectively above and below the pump piston into the working cylinder above the piston therein, and a common crank case closing the lower ends of said cylinders, said pump cylinder having a gas intake port and air intake port so located with relation to each other and with relation to the movement of the pump piston, that the pump piston moves across and opens and closes said ports and the lower of said passages in such manner as to admit gas above it and compress air below it during its downward movement, and force gas from the pump cylinder through the upper of said passages to the working cylinder and permit compressed air to flow from the pump cylinder through the lower of said passages to the working cylinder and then admit air through the air port to the pump cylinder during its upward movement. 8. An internal combustion engine having a working cylinder, a piston movable therein, a pump cylinder, a pump piston movable in the pump cylinder, cranks connected with the pistons, gearing connecting the cranks, a crank case containing the cranks, said pump cylinder having a gas port and an air intake port on respectively opposite sides of the pump piston, said cylinder being connected with the working cylinder by two passages that lead from respectively above and below the pump piston, the air and gas ports and the lower of said passages being opened and closed by the pump piston, and said ports being so located with relation to each other and to the passages that when the pistons move downwardly they cause a compression of

air, admitted through the air port, in the crank case, and when the pistons move upwardly they first admit the compressed air to the working cylinder and then compress 5 said air, and gas admitted through the gas port, in the working cylinder.

9. An internal combustion engine, having a working cylinder and a pump cylinder arranged side by side and opening into a common crank case, pistons in the cylinders, cranks and crank shafts connected with the pistons, intermeshing gears connecting the shafts, gas intake and air intake ports opening into the pump cylinder on respectively 10 opposite sides of the pump piston, a gas passage and an air passage leading from the pump cylinder on respectively opposite sides of the pump piston to the working cylinder, and an exhaust port from the latter cylinder, said ports and passages being so arranged, and the said gearing being so timed that air is compressed in the crank case by the downward movement of the two pistons, and the compressed air is admitted 15 to and with the gas is compressed in the working cylinder during the upward movement of the two pistons.

10. In an internal combustion engine, a working cylinder and a piston therein, a pumping cylinder and a piston therein, a crank case connected with the cylinders, means for reciprocating the pistons syn- 20

chronously, a port controlled by the pumping piston for admitting gas into the upper end of the pumping cylinder, a port for admitting air into the crank case, a gas passage leading from the upper end of the pumping cylinder to the working cylinder, a valve in said passage, and an air passage controlled by the pumping piston leading from the lower end of the pumping cylinder to the working cylinder.

11. In an internal combustion engine, a working cylinder and a piston therein, a pumping cylinder and a piston therein, a crank case connected with the cylinders, means for reciprocating the pistons synchronously, a port controlled by the pumping piston for admitting gas into the upper end of the pumping cylinder, a port for admitting air into the crank case, a gas passage leading from the upper end of the pumping cylinder to the working cylinder, a valve in said passage, and an air passage leading from the lower end of the pumping cylinder to the working cylinder, said pumping piston being provided with a passage therethrough adapted to connect the crank case with said air passage in one position of the pumping piston.
